UNITED STATES PATENT OFFICE.

SIMEON G. CURTICE, OF ROCHESTER, NEW YORK.

DESIGN FOR A TOP FOR CANS, JARS, &c.

SPECIFICATION forming part of Design No. 18,622, dated September 25, 1888.

Application filed July 21, 1888. Serial No. 280,660. Term of patent 7 years.

To all whom it may concern:

Be it known that I, SIMEON G. CURTICE, a citizen of the United States, residing at Rochester, in the county of Monroe, in the State of New York, have invented and produced a new and original Design for Caps or Tops for Jars, Bottles, &c., of which the following is a specification, reference being had to the accompanying drawings, forming part thereof.

Figure 1 is a plan view of a screw-top for cans, jars, &c., showing my design. Fig. 2 is a side elevation of the same.

The leading feature of my design consists in a series of curved indentures or scallops arranged around the upper edge or margin of the top, the outlines of which indentures, whether viewed in plan or in elevation, are entirely inclosed within the general form of the top.

A is the upper surface of the screw-top; B, the cylindrical wall of the same; C, the raised

screw-thread, and D the series of curved indentures surrounding the margin or edge. The number and size of the indentures may be varied according to the dimensions of the top, the general effect remaining the same, substantially as represented in the accompanying drawings. The design may be further ornamented by a circular boss on the upper surface of the top, located at the center thereto.

What I claim is—

The design for tops for cans, jars, bottles, &c., the same comprising a series of concave indentures of uniform size in the upper edge of the top, extending around the entire circumference, and entirely inclosed within the general outline of the top, substantially as set forth and shown.

SIMEON G. CURTICE.
